A. J. DONLEY

SPARK PLUG

Filed Aug. 18, 1920

FIG. 2.

FIG. 3.

Inventor

Arthur J. Donley
By *Paul R. Waller* *Attorney*

UNITED STATES PATENT OFFICE.

ARTHUR J. DONLEY, OF CHICAGO, ILLINOIS.

SPARK PLUG.

Application filed August 18, 1920. Serial No. 404,332.

To all whom it may concern:

Be it known that I, ARTHUR J. DONLEY, a citizen of the United States, residing at Chicago, in the county of Cook and State 5 of Illinois, have invented a new and useful Spark Plug, of which the following is a specification.

This invention is a device for igniting the mixture of internal combustion engines. The 10 main and important aim of the invention is a form of spark plug in which simplicity and a minimum number of parts is the objective, thus avoiding complicated and expensive construction, yet producing a plug 15 effective and efficient for its purposes.

Another object of the invention is the provision of a connecting terminal for the spark plug which will not become loose or disconnected due to vibration and which 20 will at all times maintain a good electrical connection, although readily detachable without the use of tools.

One of the features of the invention resides in a sleeve or tubular member embedded in the insulating block of the plug, and forming a socket and an electrode embedded in the lower portion of the block with its upper end terminating at the lower 25 end of said tube and in substantial alignment with the longitudinal axis thereof, thereby forming an intensifying gap between the lower end of the tube and the upper end of the electrode.

Another feature of the invention resides 30 in said tubular socket being adapted to receive a plug terminal which extends therewith into a frictional sliding fit thus enabling quick attachment and detachment of the terminal without the need of tools and 35 the labor now required by other spark plugs, and eliminating washers, nuts, threaded rods and clamps which work loose through vibration and destroy the electrical connection.

The invention further resides in the sundry details of construction, organization, and combination of parts hereinafter more 40 fully described.

In this specification and the annexed 45 drawings, the invention is disclosed in the form in which it is considered to be the best, but the invention is not limited to

such form because it is capable of being embodied in other forms; and it is to be understood that in and by the claims following 55 the description herein, it is intended to cover the invention in whatever form it may embody within the scope thereof.

In the drawings:

Figure 1 is a longitudinal sectional view 60 taken through the spark plug constructed in accordance with the invention,

Fig. 2 is a transverse sectional view taken substantially on line 2—2 of Fig. 1, and

Fig. 3 is a perspective view of the insulating block.

The spark plug comprises a hollow metallic member or casing 1, externally threaded at its inner end and provided at its opposite end with a polygonal head to receive a 70 wrench in the placing and removing of a plug. This casing has suitably secured to its lower end an inwardly lateral extending arm 2 providing one of the electrodes of the 75 plug, in a manner which is usual in connection with the devices of this character.

The insulating plug 3 is formed of fiber, porcelain or other suitable material, and has an exterior contour which is common to most plugs, that is having an enlarged central portion forming a shoulder 4, which rests on a shoulder 5 provided on the interior of the casing 1. A binding nut 6 fits over the upper end of the casing. This binding nut engages on the opposite side α 80 of the shoulder 4, to clamp the insulating block firmly in the casing against the shoulder 5 thereof, there being a suitable washer or gasket 7 between the shoulders 4 and 5 so as to provide an air and gas-tight joint.

The insulating block is formed also with a longitudinal bore, substantially the upper half of the bore being enlarged, in the manner shown in the drawings. A metallic tube 85 90 95 100 105 8, of any suitable material which is a good electrical conductor is tightly fitted in the upper or enlarged portion of the bore and is held in place by cement or in any other suitable manner, the upper end of the tube 8 terminating and being flush with the upper end of the insulating block.

In the lower portion of the bore is tightly fitted the other electrode 9, of the plug end,

as will be observed from the drawings, lies in substantial alinement with the longitudinal axis of the tube 8, having the upper or inner end thereof terminating slightly within the lower end of the tubular member, while its lower end projects for a distance beyond the lower end of the insulating block to cooperate with the electrode 2 for the purpose of producing an electrical spark for igniting the explosive mixture in the combustion chambers of the engines.

It will be observed that the tubular member 8 provides a socket to receive a connecting terminal, and, by reason of its disposition and relation relative to the electrode 9, an auxiliary spark gap is provided between its lower end and the upper end *a* of the electrode 9, which intensifies the spark occurring at the point *b* in the combustion chamber.

It will also be observed that the construction of the insulating block, just described, is extremely simple, possessing but three elements which may be assembled with extreme ease without necessitating skilled workmen and can be produced at a very low cost, while at the same time provides a spark plug with an intensifying gap which has heretofore only been provided with considerable additional cost.

The tubular or socket member 8 receives the projecting end 10 of a plug terminal 11. The end 10 of the terminal preferably has the same cross section as the socket and is of any suitable conductive material and is suitably slotted as at *c*, to give it a lateral resiliency in order that the end 10 will tightly and frictionally engage the interior wall of the socket 8. This connection of the terminal 11 with the spark plug permits of a rotating or oscillating movement between the end 10 of the terminal and the socket, thereby having a free movement to compensate for any torsional twist, or strain on the terminal caused by vibration. Moreover, this terminal connection permits ready attachment and detachment of it from the spark plug by a mere longitudinal pull on the terminal and eliminates all nuts, washers, threaded rods, clamps and other similar cap members which require considerable effort and tools to manipulate. Furthermore, the ordinary spark plugs having clamps and screw-threaded parts for securing the terminal to the plug, require constant attention because the terminal works loose by reason of the vibration set up by the engine and traction, and destroys the electrical connection. It is readily appreciated that this is the source of constant annoyance and often causes the engine to knock and jolt, and the operator usually goes to considerable work and inspection before he has realized that the trouble is due to a loose connection with a spark plug.

By reason of this terminal connection the liability of short-circuiting is largely reduced because the insulated and enlarged handle portion *d* of the terminal overlies the upper end of the tubular socket 8, and abuts the upper surface of the insulating block 3, as clearly shown in Figure 1. In the usual type of spark plug the opposite end of the electrode projects from the upper end of the insulating block, and should a tool or other piece of metallic material come in contact therewith it short-circuits the spark plug. Moreover the upper end of the electrodes in the usual spark plug very often becomes broken off and thereby destroys the plug.

From the foregoing it will be apparent that the spark plug according to the present invention is extremely simple and that the tubular member 8 forms a two-fold purpose of providing a socket having an improved terminal connection with the plug, and for providing an intensifying gap for the current. It will further be apparent that after the life of the plug of this invention, the entire plug need not be discarded, but may be repaired by simply removing the lock-nut 6 and then withdrawing the insulating block 3, which is extremely inexpensive and may be supplied at one-fourth the cost of new plugs.

What I claim is:

1. As an improvement in spark plugs, an insulating block, an electrode in said block, an electro-conductive tubular member forming a terminal socket in said block and spaced from the electrode to provide an intensifying gap with the latter, and an electro-terminal plug removably inserted in said tubular socket and in electrical contact therewith and out of contact with said electrode.

2. As an improvement in spark plugs, an insulating block, an electro-conductive tubular member forming a terminal socket in said block, an electrode in said block and arranged in substantial alinement with the longitudinal axis of the tubular member and entering the lower end of the socket for providing an intensifying gap, and an electro-terminal plug removably inserted in said socket.

3. As an improvement in spark plugs, an insulating block, an electro-conductive tubular member forming a terminal socket in said block, and an electrode in said block having its inner end extending in the inner end of said tubular member for providing an intensifying gap with the latter, and an electro-terminal plug removably inserted in said tubular socket and in electro-contact therewith and out of contact with said electrode.

4. As an improvement in spark plugs, an

insulating block having a longitudinal bore therein, the upper portion of said bore being enlarged, an electro-conductive tubular member secured in the enlarged portion of the bore, an electrode in the smaller portion of said bore, the inner ends of said tubular member and electrode being positioned rela-

tive to each other to provide an intensifying gap and an electro-terminal plug removably inserted in said tubular member. 10

In testimony whereof I have hereunto set my hand.

ARTHUR J. DONLEY.
